DESIGN.

A. W. PATCHING.

CLASP OR BUCKLE FOR BELTS OR SASHES.

No. 20,094.

Patented Aug. 12, 1890.

UNITED STATES PATENT OFFICE.

ALEXANDER W. PATCHING, OF BIRMINGHAM, ENGLAND.

DESIGN FOR A CLASP OR BUCKLE FOR BELTS OR SASHES.

SPECIFICATION forming part of Design No. 20,094, dated August 12, 1890.

Application filed June 16, 1890. Serial No. 365,646. Term of patent 7 years.

To all whom it may concern:

Be it known that I, ALEXANDER W. PATCHING, a subject of the Queen of the United Kingdom of Great Britain and Ireland, residing at Birmingham, England, have invented and produced a new and original Design for Clasps or Buckles for Belts or Sashes, of which the following is a specification, reference being had to the accompanying drawing, forming part thereof, which represents a front view of my design.

The design includes novelty in both the contour and surface ornamentation of a clasp or buckle of a sash. The link is shown at 1. It has a narrow but slightly-flaring end 2 and an expanded portion 3. The part 2 has longitudinal lines 4 and surrounding-lines 5, which

represent leather bands, this part being intended to represent the handle of a tennis-racket. The expanded end of the link has 20 ridges crossing each other rectangularly and made to simulate the woven work of a racket. The outer border of this expanded part is smooth and is raised somewhat above the level of the representation of weaving. 25

6 represent cross-bars, and 7 a sash, band, or belt extending from the cross-bars.

What I claim is—

The design for a clasp or buckle, substantially as herein shown and described.

ALEXANDER W. PATCHING.

Witnesses:

JOHN F. PATCHING,
A. S. WALKER.
